UNITED STATES PATENT OFFICE.

FREDERICK W. MARTIN, OF WAUKEGAN, ILLINOIS.

STEERING APPARATUS FOR VESSELS.

SPECIFICATION forming part of Letters Patent No. 398,900, dated March 5, 1889.

Application filed April 23, 1887. Serial No. 235,930. (No model.)

To all whom it may concern:

Be it known that I, FREDERICK W. MARTIN, a citizen of the United States, residing at Waukegan, in the county of Lake and State 5 of Illinois, have invented a new and useful Center-Board Steering-Gear for Sail-Boats, of which the following is a specification.

My invention relates to improvements in steering-gear for small sailing-boats; and the 10 objects of my improvements are, first, to provide extra room in the boat by removing forward the center-board that hitherto has occupied so great a space in the center of the boat; second, to dispense with the deck steering-gear, now in common use; third, to dispense with steering-gear entirely when one wishes to use the sail-boat as a canoe; fourth, to make beaching and launching easy, and, fifth, to increase 15 speed and steadiness in sailing. I attain these 20 objects by the mechanism illustrated in the accompanying drawings, in which—

Figure 1 is a longitudinal section of a boat rigged with my steering-gear. The relative length of the boat as compared with the length 25 of the rudders or "center-boards" is in practice much greater than appears in the figure. Fig. 2 is a plan view of the upper portion of the gear. Figs. 3 and 4 are vertical cross-sections 30 of a boat rigged with my gear. Figs. 5 and 6 are plan views of the boxes in which the rudder-stocks revolve. Fig. 7 is a plan view of 35 the parts of the keel above the rudders or center-boards.

Similar letters refer to similar parts throughout the several views.

In Fig. 1 A and B represent, respectively, 40 the aft and forward center-boards; C, the hull of the boat; D, its deck; E, its keel; F, the forward center-board trunk; G, the aft center-board trunk; H, the tiller; K, the stock on which the aft center-board is fixed; L, the stock on which the forward center-board is fixed; M and M', the boxes that contain the washers X and X', through which the stocks 45 pass; O, a drop-joint in L and O', showing the position of the upper part of L when B is elevated into F; P, a part of L rounded; Q and Q', halyards used in raising A and B; R, cleats; A' and B', dotted lines showing position 50 of A and B when raised into G and F; K', the position of the stock of the aft center-board when the latter has been raised into G,

and L' the position of L after B has been raised in like manner and before the drop-joint has been used.

In Fig. 2 H represents the tiller; S, a yoke fixed at right angles on the stock of the aft center-board; I and I', lever quadrant cog-gears; J, a gear cog-wheel; S', a transverse section of L; V' and V'', pulleys, and T and T' connecting-gear.

In Fig. 3 is seen a vertical cross-section of the boat near the stern through the aft center-board, showing the aft part of the steering-gear as seen from the stern.

In Fig. 4 is seen a vertical section of the boat through the forward center-board, showing the forward part of the steering-gear as viewed from the direction of the stern. p p are beams supporting the lever quadrant cog-gears. In Fig. 5 U' represents a plan view 70 of the box M after its top has been taken off; M'', this top, and K' a transverse section of K in the washer X.

In Fig. 6 we have U', M'', and X again, together with S', a transverse section of L.

In Fig. 7 E is the keel, and N represents plates screwed to this on either side of the slots that allow the center-boards to pass up 80 into their trunks, and Z Z are apertures in the plates, through which K and L pass and in which they revolve.

The blades A and B are designed to be used both as rudders and as center-boards. Their use as the latter is too obvious to require explanation. I proceed to explain their use as rudders.

Referring to Fig. 2, if H is moved to the line a a, A will stand in the plane a a, and S in the plane e e. T will have therefore drawn 90 the lever I to the line g. Thus the lever cog-gear I will be made to turn J partly around. Now J has a rectangular hole through its center, and L is rectangular except at P, and is of such size as to fit (but not tightly) in 95 this hole; hence when the above movements have taken place B will stand in the plane d d. Thus the course of the boat will be directed toward the port. Reversing above operation, it will be turned in the starboard direction. Turning the tiller at the proper angle and holding it still, the boat may be made to describe a circle of greater or less diameter, according as the angle of the blades with

the longitudinal axis of the boat is less or greater. When running before the wind, the board B may be raised and housed in the trunk F. At P, Fig. 1, L is made round, so that when B is thus housed the cog-wheel J may revolve without at the same time turning the stock L. Thus A acts as the sole rudder (and at the same time as a center-board) and so keeps the craft from "yawing" in a sea-way and holds it more steady than it would be with any steering-gear now in use.

If it is desired to row or paddle the boat absolutely, both A and B may be unshipped by unscrewing the nuts k and k' and drawing them (A and B) out and entirely detaching them from the boat. A and B are housed in G and F whenever the boat is beached, thus avoiding the inconvenience occasioned by a rudder when beaching and launching a boat.

20 The forward stock, L, is provided with a drop-joint, O, so that when B is housed, to sail before the wind, the upper section of L may be dropped, as shown at O', and thus prevented from coming in contact with the boom of the sail.

With my steering-gear the lateral resistance is fixed at such distance apart in the boat that it is made to move more steadily in a seaway, and consequently will sail faster.

30 Instead of the lever cog-gears I and I' a single yoke can be used on forward or after side of cog-wheel J with quadrant attachment, but not so effectually as by the mechanism shown in the drawings herein.

35 Having fully described my invention, what I desire to claim and secure by Letters Patent is—

1. In machinery for steering boats, the box M, fastened to the under side of the deck of the boat, its interior surface being circular in form and vertical in position, so as to permit the washer X to revolve therein, and being also of such diameter as to afford the said washer the least practicable lateral motion, said washer being pierced with a hole of such size and shape that it fits loosely upon the rudder-stock K, which bears the rudder-blade A and revolves with said rudder-stock, steady-ing its motion, and allows it to pass upward

and downward in the trunk G, substantially as shown, and for the purposes specified.

2. In machinery for steering boats, the yoke S, fastened tightly on the rudder-stock K and connected by means of the yoke-lines T and T' with the lever-gears I and I', which engage with the cogs of the gear-wheel J on its opposite sides, substantially as shown, and for the purpose specified.

3. The lever-gears I and I', fastened beneath the deck of the boat, in combination with the yoke S, by means of the connecting yoke-lines T and T', and engaging by their cogs with the cogs of the gear-wheel J, said gear-wheel being provided with an angular hole through its hub, of such diameter as to permit the rudder-stock L to easily pass through and also to cause it to revolve when the said gear-wheel J revolves, substantially as described, and for the purposes specified.

4. In machinery for steering boats, the rudder-stock L, angular in form except at its lower extremity, P, and of such diameter as to pass through and fit loosely in the hub of the gear-wheel J, and the washer X', said stock passing through the box M' and the trunk F, and being fastened at its lower end to the rudder-blade B, substantially as shown, and for the purposes specified.

5. In machinery for steering boats, the box M', fastened beneath the deck of the boat and containing the washer X', in combination with the rudder-stock L, passing through them, substantially as shown, and for the purposes specified.

6. The drop-joint O in the rudder-stock L, constructed near the middle of the same, and the cylinder-shaped section P of the rudder-stock L, made at its lower end, substantially as shown, and for the purposes specified.

7. In machinery for steering boats, the chains Q and Q', in combination, respectively, with the rudder-blades A and B, substantially as shown, and for the purpose specified.

FREDERICK W. MARTIN.
